STEAM GENERATOR

Arthur E. Duram, Springfield, Ill., assignor to
 Springfield Boiler Company, Springfield, Ill.,
 a corporation of Illinois

Application October 21, 1936, Serial No. 106,711

2 Claims. (Cl. 122—235)

This invention relates to steam generators or boilers and is particularly directed to apparatus of this kind of large capacity and high rating. Heretofore such generators have frequently been supplied with auxiliary devices or attachments such as super-heaters, economizers or air heaters, which devices have been attached or positioned in various relationships with the steam producing elements or boiler settings. The present invention contemplates a steam generator having such devices arranged substantially within the confines of the boiler setting in order to overcome objectionable features of such previous apparatus and to provide an improved boiler which will be comparatively simple in construction and particularly efficient in operation.

Other objects are to provide a steam generator having a novel arrangement of auxiliary attachments such as super-heaters, economizers and air heaters, and means to control the gases passing through such devices; to provide an improved steam generator or boiler of high capacity, high pressure, and relatively high temperature with means for controlling the gases to the super-heater and other parts; to provide a boiler having auxiliary equipment comprising a super-heater, economizer and air heater arranged in series in the gas flow above the tube bank of the boiler and below the steam and water drum, and within the reasonable confines of the boiler setting; to provide a boiler of the character indicated having a novel arrangement of tubes; to provide a by-pass and other connections; and in general to provide such improvements and desirable features as will be described more fully hereinafter.

In the accompanying drawings illustrating this invention,

Figure 1 is a longitudinal sectional view with parts shown diagrammatically or omitted for convenience in illustration; and

Figure 2 is a similar view showing a modified form with the drum in a different position and other parts arranged accordingly.

The main boiler 5 includes a front header 6 and rear header 7 connected by a bank of tubes 8 and adapted to be supplied with heat from a furnace 9 which may be supplied with any suitable combustion apparatus (not shown) such as used for boilers of this type. The header 6 is connected to a header 10 by means of vertical tubes 11 and the header 10 is connected to the boiler drum 12 by horizontal tubes 13 which pass along the top of the boiler, the drum 12 being positioned substantially over the header 7.

Some of the upper tubes 14 which are connected to the rear header 7 extend toward the front of the boiler and then upwardly to form a vertical wall or bank and then rearwardly to connect with the drum 12. The vertical portions of these tubes are provided with insulation or blocks to form a partition 15 that extends from approximately the top of the main bank of tubes 8 to a point somewhat below the tubes 13, thus providing a passageway 16 at the front of the boiler setting as clearly shown in Figure 1.

Another group of tubes 17 extend from the rear header 7 to a point slightly back of the vertical bank of tubes 14 and then upwardly, and are connected with the drum 12 the same as the tubes 14. The tubes 17 are also provided with insulation, blocks or the like, to form a partition or wall 18 which is parallel to the wall 15 and these two water cooled partition walls define a vertical by-pass 19 to by-pass gases from the passageway 16. The flow of gases through the by-pass may be controlled in any suitable manner as by means of a damper 20 which may be provided with any suitable controlled or operating means. The upper row of tubes 21 from the rear header 7 also extend for a short distance parallel to the tubes of the main bank and then upwardly and then rearwardly and are connected to the drum 12 to form down-comers from the drum to the headers. The vertical portion or bank of tubes 21 is also provided with insulation blocks or the like to form a partition 22 which terminates at a short distance from the top bank of the tubes 8 but extends upwardly to the tubes 13 or to the top of the boiler setting and thus provides a passageway 23 which is substantially parallel to the passage 16. A baffle or wall 24 is positioned above the tubes 8 and extends from the header 7 or rear of the boiler setting to the wall 18 so as to direct the gases to the passageway 16 and by-pass 19.

It will be noted that the partition 22 is located at a sufficient distance from the back of the boiler setting to provide a third passageway 25 which is provided with a gas outlet 26. This arrangement is such that the gases of combustion pass up through the passageway 16 when the by-pass is closed, then over the top of the by-pass and down through the passageway 23, then under the wall 22 up through the passageway 25 and out through the outlet 26. When the damper 20 is opened a portion of the gases will pass through the by-pass and thus reduce the amount of gases or heat supplied to the chamber or passageway 16.

A super-heater 21 of any suitable type is positioned within the chamber or passageway 16 and is connected to the drum 12 by tubes 28 and is provided with an outlet pipe 29 for connecting the same with an engine or other apparatus to be supplied with steam.

An economizer 30 of any ordinary or preferred form is positioned within the chamber or passageway 23 and provides means for heating the feed water by the waste gas. The economizer has an inlet or supply pipe 31 which is connected with a boiler feed pump or the like (not shown) and has an outlet pipe or connection 32 to the drum 12. An air heater 33 is positioned within the chamber or passageway 25 and is supplied with heating gas which passes from the passageway 23 under the partition 22 and up through the heater before it escapes through the outlet 26. The air heater may be of the plate type such as indicated, or of any other suitable type and is shown as having an air inlet 34 which may be supplied with air from a forced draft fan. The outlet 35 is connected in any suitable manner to supply air to the furnace or fuel burning equipment. It will be understood that the drawings are intended generally to represent the upper section of a standard boiler and that the same is supplied with such additional connections or controlling devices as commonly used for such apparatus.

In generating apparatus of this type it has been found particularly desirable to provide means for controlling the amount of gas or heat supplied to the super heater. In accordance with this invention, if the damper or control device 20 is closed, all of the gases from the furnace pass up through the main boiler tubes and then through the passageway 16, then down through the passageway 23 and the economizer 30 and then up through the passageway 25 and the air heater 33 and out through the outlet 26. If it is desired to reduce the amount of heat supplied to the super heater the damper 20 is opened any desired amount which permits a portion of the gases of consumption to be by-passed through the by-pass 19, thus reducing the amount supplied to the super heater, but in either event all of the gases continue through the economizer and air heater as described. The provision of the water cooled walls on either side of the by-pass prevents the burning out of these walls and at the same time the heat from the gases will be utilized to heat the water or steam in the bank of tubes 15 and 17, thus tending to utilize the heat as well as to increase the circulation in the boiler.

The modified form of construction shown in Figure 2 is substantially the same as above described but shows a slightly different arrangement which might be found advantageous in certain installations. In this construction the drum 12a is moved forward and the down-comer tubes 21a extend directly down from the bottom of the drum instead of being bent to connect therewith

as shown in Figure 1. The gas outlet 26a is then extended up at the rear of the drum, as shown. The operation is substantially the same as described in the apparatus shown in Figure 1. In both forms it is of course understood that the boiler setting is suitably arranged in substantially the usual manner in order to properly enclose the various elements. It will also be noted that the present invention is directed to the general construction and arrangement of the steam generator as a whole and to the positioning of the several units or auxiliary devices rather than to the specific construction of any of such devices. It will also be noted that changes may be made in the arrangement of the parts and in some instances one or more of the auxiliary features may be omitted without departing from the scope of this invention so that the invention should not be limited to the particular arrangement herein shown and described except as specified in the following claims in which I claim:

1. A tubulous boiler of the character set forth, including a rear header and a drum, having some of the upper tubes extending forwardly from the rear header and then upwardly to provide parallel banks with a space between the same, the upper ends of the tubes being connected with the drum, a baffle from the rear header to the rear bank of said vertical tubes, partitions secured to the tube banks to provide a by-pass around the front gas passageway, a damper for controlling the by-pass, down-comer tubes extending from the rear header upwardly to provide a parallel bank spaced from the by-pass and connected with the drum, a partition secured to the down-comer tubes and extending upwardly to the top of the boiler and terminating above the baffle, said partitions being arranged to provide three passageways in series at the top of the boiler, the last passageway being provided with an outlet, and auxiliary apparatus positioned in said passageways.

2. The combination with a boiler having front and rear headers connected by a main bank of tubes and having a drum positioned above the rear header and all enclosed in a setting, of down-comer tubes from the drum to the rear headers forming a vertical bank, riser tubes from the rear header extending upwardly in front of the down-comer tubes and arranged to provide parallel banks adjacent to each other, partitions connected with said banks, and baffles associated therewith to divide the upper part of the boiler setting into three main passageways for series flow of the gases, and a by-pass around the front passageway, means for controlling the flow through said by-pass, a super heater positioned in the front passageway, an economizer positioned within the intermediate passageway, and an air heater positioned within the last passageway.

ARTHUR E. DURAM.
